UNITED STATES PATENT OFFICE.

CHESTER E. McGOWAN, OF MEMPHIS, TENNESSEE.

METALLIC SASH-BAR.

1,268,032.

Specification of Letters Patent. Patented May 28, 1918.

Application filed October 13, 1915. Serial No. 55,639.

To all whom it may concern:

Be it known that I, CHESTER E. McGOWAN, a citizen of the United States, residing at Memphis, in the county of Shelby 5 and State of Tennessee, have invented a certain new and useful Improvement in Metallic Sash-Bars, of which the following is a specification.

My present invention pertains to an improved metallic sash-bar, the construction and advantages of which will be hereinafter set forth in detail.

The main object of the invention is to produce a strong yet relatively light bar, one 15 simple in form and embodying a minimum number of parts.

A further object is to provide a structure which will ventilate the window and likewise drain the same.

20 A still further object is to provide a screen, preferably housed within the bar, to prevent the ingress of dust and insects through the vent and drainage openings.

Another object is to provide a slide to 25 control the vent openings, whereby they may be closed when required.

The structure is shown in the annexed drawings, wherein:

Figure 1 is a sectional perspective view 30 of a portion of the bar and window-pane, and of the sill or store-front proper; and

Figs. 2 to 7, both inclusive, sectional views of different embodiments of the invention.

Similar reference numerals will be employed throughout the various figures to indicate similar parts.

The bar may be said to comprise two parts; a body portion, formed from a single piece of metal bent or otherwise brought to 40 form, embodying a shelf for supporting the pane, a back stop or pane-engaging member, and a gutter, combined with a front, pane-engaging molding, the body portion being secured directly or indirectly to the window 45 framing or sill; while the front molding is secured to the main body portion or member, or some member fixed relatively to the body member or sill.

Referring first to the construction illustrated in Fig. 1, 10 denotes the sill and 11 the flooring of the window. The combined back stop and shelf of the bar is formed from a single piece of comparatively light 55 metal, preferably copper, and consists of a base plate 12, a vertical front wall 13, a

shelf 14, and a forwardly-inclined pane-clamping member, bead or back stop proper, 15, the upper edge 16 whereof is turned over and downwardly, clamping between its folds the edge of the upwardly-extending 60 gutter member 17. Said member 17 extends from the lower forward portion of the perforate gutter member 18, which latter is turned inwardly from the back wall 19, rising from the base plate 12. There is thus 65 produced a hollow structure or bar, consisting of a base proper formed by members 12, 13 and 19, surmounted by a shelf, a back stop and a gutter. Wall 19 is preferably formed with an inwardly-extending bead 70 20, which not only stiffens said wall but also forms the support for one edge of a wire gauze screen 21, interposed between the rear wall 19 and the rear or inner face of the back stop or member 15. Member 18 is 75 provided with a series of openings 22, and the front wall at its lower portion is likewise provided with perforations 23, these two series providing for drainage and ventilation, and the screen arresting the passage 80 into the store window of dust and insects through the openings 22.

The glass pane is denoted by 24, and rests upon blocks of wood, leather or other suitable material 25, interposed at intervals between its lower edge and the shelf 14.

The face molding may be of any approved type, but preferably will be provided with a clamping lip 26, extending upwardly and inwardly from the body, denoted as a whole 90 by 27. In the type illustrated the face molding is formed with a horizontal channel 28, adapted to house the heads of screws 29, which pass through openings in said channel, and through aligned openings 30 and 31, 95 provided, respectively, in the vertical walls 13 and 19 of the combined back stop and supporting shelf, and into the flooring 11, or other corresponding element. The lower, forward portion of the molding is provided 100 with a series of openings 32, to complete the drainage and ventilating system.

As will be noted upon reference to all the figures, the glass is held between the edges of bead 15 and lip or flange 26, and said members contact with the glass at points or lines remote from the edge thereof. By reason of this arrangement, breakage owing to pressure brought about by expansion due to heat is minimized, while at the same time the 110

glass is firmly held at all times and under all weather conditions.

The construction is at once strong and simple and is easy of placement.

5 In Fig. 2 I have shown the same general arrangement but in addition have provided a perforated slide 33, located in the upper rear portion of the back stop or body member, by the manipulation of which slide the 10 openings 22 may be closed. Ventilation is desirable in cold weather, to keep the inside surface of the glass pane as cool as the outside (or approximately so), in order to prevent condensation, but when there is no condensation the slide may be shifted to close the openings and prevent the ingress of air therethrough. When the window is being washed, the slide will be opened to permit the outflow of the water.

20 Under some conditions it may be desirable to secure the combined back stop and supporting shelf to the sill instead of to the window flooring, in which case a construction or arrangement such as illustrated in 25 Figs. 3, 4 and 5 may be employed. In Fig. 3 the combined shelf and back stop is secured to the sill 10 by screws 34, openings 35 being provided in the shelf for the introduction of the screws. Housed within 30 the body is a channel bar 36, which will likewise have openings 37, and machine screws 38 are passed through the face molding and front wall 13, and into threaded openings in the forward member of the bar, whereby 35 the parts may be drawn to position. Bar 36, having an extended bearing on wall 13 throughout its length, prevents undue strain being exerted upon the wall and distortion of the parts. The forward lower edge of 40 the channel bar 36 will preferably be notched, as at 39, for the purpose of drainage and ventilation.

In Fig. 4 a somewhat similar construction is illustrated, wherein an inverted T bar 40 45 is employed and secured to the sill by screws 34. Machine screws 38 take in threaded openings in the vertical member of the bar and draw the parts to place.

In Fig. 5 the combined back stop and shelf 50 is secured directly to the sill by screws, and the rear wall 19 is provided with a countersunk recess 42, adapted to receive nuts 43 into which bolts 44, passing through the face molding and the front wall 13, are 55 screwed. The countersunk recess stiffens the rear wall, the same as the bead 20 in the other constructions.

Under all the constructions thus far set forth it will be noted that the joint in the 60 combined back stop and shelf is formed at the junction of the back stop member 15 and the upstanding element or member 17 and this by clamping the upper edge of 17 between the back stop and the overturned upper 65 edge 16 thereof. This construction pro-

duces a stiffening effect in the back stop and gutter, rendering them rigid.

In Fig. 6 I have disclosed a further modification, wherein the back stop is formed with a rearward, horizontally-extending member 50, the rearmost edge whereof is bent or clamped, as at 51, upon and over the upper edge of the rear wall 19^a. Said member 50 may be provided with openings 22^a, which for the purposes of ventilation 75 and drainage coöperate with the other openings 23 and 32, as in the previous constructions.

Under the constructions disclosed in Figs. 1, 2, 6, and also in Fig. 7, nails as 55 are 80 passed through the front wall 13, the back wall 19 and into the flooring 11, thereby initially securing the combined back stop and shelf in place. Said nails are so located that they directly underlie the shelf 14 and tend 85 in a measure to prevent the same from sagging under the imposed weight of the plate.

With the construction shown in Fig. 6, the openings for the fastening screws 29 are located at such height that the body of the 90 screw directly underlies the shelf 14 and acts in conjunction with the nails just mentioned to support the shelf against sagging movement due to the weight of the plate.

In Fig. 7 the joint between the edges of 95 the sheet from which the combined back stop and shelf are produced is at the lower forward corner. The horizontally-disposed member 52 of the back stop under this construction may lie in the same plane as the 100 window flooring, thus producing a smooth, flush and even finish.

Under this construction and also that shown in Fig. 6, the horizontally-disposed member (52 or 50) produces a rigid back 105 stop, which, of course, is present in the other constructions, owing to the imposing of the member 15 upon the member 17, and the clamping of the two together by the overturned edge 16.

Under all the constructions it is to be noted that the back stop presents a line contact with the plate and that at a point sufficiently removed from the edge of the plate to prevent breakage thereof. Such line is 115 opposite the line contact effected by the member 26 of the face molding.

It is evident from the foregoing that in so far as the generic invention is concerned it may be varied in detail without departing 120 from the spirit of the invention, and the broader claims are to be construed in light hereof.

It is likewise evident that while the structure may be produced from light material, 125 it is strong and durable; and any tendency for the shelf 14 to sag is counteracted by the back stop member 15 and the gutter elements 17 and 18, to the first of which said member 15 is secured.

Having thus described my invention, what I claim is:

1. In a metallic sash-bar, the combination of a combined shelf and back stop for a plate 5 of glass, with the back stop portion presenting a contact line to the plate removed from the edge of the plate, said combined shelf and back stop being produced from a single piece of metal brought to form, with the 10 edges thereof secured to each other; a face molding; and means for securing said molding in place with reference to the plate supported by the shelf.
2. In a metallic sash-bar, the combination 15 of a hollow combined base, shelf and back stop produced from a single piece of metal brought to form and having the edges thereof interlocked; a face molding, said molding and back stop having opposing line contact 20 with the plate of glass supported by the shelf; and means for securing said molding in place with reference to said shelf and back stop.
3. As a new article of manufacture, a combined shelf and back stop for use in metallic 25 sash-bars, produced from a single sheet of metal bent to form and having its edges interlocked and presenting a hollow base, a shelf thereon, and a back stop extending upwardly and inwardly from the shelf at one 30 side thereof.
4. As a new article of manufacture, a combined shelf and back stop for use in metallic sash-bars, produced from a single sheet of 35 metal bent to form and presenting a hollow base, a shelf thereon, and a back-stop extending upwardly from the shelf at one side thereof and inclining toward the opposite edge of the shelf, the proximate edges of the 40 sheet being secured together.
5. As a new article of manufacture, a combined shelf and back stop for use in metallic sash-bars, produced from a single piece of metal bent to form and presenting a hollow 45 base, a shelf thereon, a back stop in rear of said shelf, and a gutter in rear of the back stop, the proximate edges of the sheet being secured together.
6. In a metallic sash-bar, the combination of a base, a shelf, and a back-stop all produced from a single piece of metal bent to form, with the proximate edges thereof interlocked; a rib or bead formed upon the rear wall of the base; and a wire screen supported at one edge by the bead and at its 55 opposite edge by the inner wall of the back-stop. 50
7. In a metallic sash-bar, the combination of a base, a shelf, a back stop, and a gutter, all produced from a single sheet of metal 60 bent to form; a rib or bead formed upon the rear wall of the base; and a wire screen supported at one edge by the bead, and at its opposite edge by the inner wall of the back stop. 65
8. In a metallic sash-bar, the combination of a combined base, shelf and back-stop, produced from a single sheet of metal bent to form; a face molding; a structural element housed in the base of said combined member; 70 and means acting in conjunction with said structural member for securing the face molding in place.
9. In a metallic sash-bar, the combination of a combined base, shelf and back stop, produced from a sheet of metal bent to form; a structural element housed in said base; means for securing said element and combined member to a sill; a face molding; and means acting in conjunction with said structural element for securing the face molding in place. 75
10. In a metallic sash-bar, the combination of a hollow combined base, shelf and back stop produced from a single piece of metal 85 brought to form and having the edges thereof interlocked, the back stop inclining inwardly over the shelf; a face molding, said molding and back stop having opposing line contact with the plate of glass supported by 90 the shelf; and means for securing said molding in place with reference to said shelf and back stop. 80

In testimony whereof I have signed my name to this specification.

CHESTER E. McGOWAN.
